Patented Feb. 27, 1968

210,320

COMBINED MAGNETIC AND CYCLONE SEPARATOR FOR MACHINE TOOL COOLANTS AND THE LIKE

Harry J. Collins, Jr., Milwaukee, Wis., assignor to Barnes Drill Co., Rockford, Ill., a corporation of Illinois

Filed Dec. 19, 1966, Ser. No. 5,101

Term of patent 14 years

(Cl. D55—1)

FIGURE 1 is a front perspective view of a combined magnetic and cyclone separator for machine tool coolants and the like incorporating my new design.

FIG. 2 is a side elevational view.

FIG. 3 is a top plan view, and

FIG. 4 is a rear perspective view thereof.

I claim:

The ornamental design for a combined magnetic and cyclone separator for machine tool coolants and the like, substantially as shown.
